Attorney.

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

LEDGER SHEET.

1,416,239.

Specification of Letters Patent. Patented May 16, 1922.

Application filed May 16, 1919. Serial No. 297,469.

To all whom it may concern:

Be it known that I, JESSE A. B. SMITH, a citizen of the United States, residing in Stamford, in the county of Fairfield and 5 State of Connecticut, have invented certain new and useful Improvements in Ledger Sheets, of which the following is a specification.

This invention relates to bookkeeping devices, and is herein illustrated as applied to a loose-leaf "Boston" ledger such as is used for bank-bookkeeping, and as especially adapted to be used in connection with an Underwood standard bookkeeping machine.

15 "Boston" ledgers comprise sheets which have horizontal rulings to divide them into spaces, so that there is a horizontal space between each two lines of ruling for each account on the ledger. These ledgers are 20 also provided with vertical rulings to divide the horizontal spaces into columns for days, a column or columns for names, and other minor columns. Each day column is usually further divided into two or three subsidiary columns. As shown herein, these 25 subsidiary columns are two in number, one to receive the items of charges and credits, or checks and deposits, the other column to show the current daily balance.

30 In order to enable a sheet of this character to be utilized to advantage in a typewriter bookkeeping machine, it is preferable to provide a column adjacent the daily balance column of each day, in which the "pick-up" 35 balances can be written, while transferring the current daily balance into a computing register, preparatory to adding thereto or subtracting therefrom the next item to be entered in the checks-deposit column. A "pick-up" column, when thus utilized, enables the typist to visually verify the copying of the daily balance into the computing register, and by having the "pick-up" column adjacent the daily balance 40 column, the detection of errors in this copying is greatly facilitated.

Since these "pick-up" column entries are of no permanent value after the daily balance has been checked up, it is usually both 45 a waste of space on the sheet written, and a waste of valuable storage room, to keep the written "pick-up" balances as part of the permanent records. Besides this, if the sheet is made wide enough to accommodate

the "pick-up" columns on its body, it becomes so wide as to become awkward to manage, and requires an exceedingly wide carriage in the computing machine which is to receive it.

With these and other limitations in mind, 55 I have found it possible to design a ledger-sheet which shall comprise an integral extension or portion adapted to receive "pick-up" balances. This portion may be so located and attached that it may readily be 60 shifted out of the way at the end of the day's work, or at the beginning of the succeeding day's work, or at such other times as desired.

In carrying out this invention, I have 65 found it advantageous to provide a single extension or flap attached to one edge, preferably the upper edge, of the ledger-sheet, and adapted to be folded over so that it may be used to receive the "pick-up" 70 balances on either face of the sheet. This flap or extension may be in the form of an extra sheet pasted to the ledger-sheet proper, and may be divided into columns, each adapted to just cover up a single day column, thus 75 permitting the flap overlying one day column to be used as a temporary "pick-up" balance memorandum of the daily entries in the adjoining day column.

The flaps or extensions thus attached may 80 be formed from a single sheet which is kept integral, for convenience in handling, until it is severed along perforated lines which coincide with the edges of the day columns.

This form of "pick-up" column memorandum sheet is only a single thickness, in addition to the usual ledger-sheet, and this additional thickness may be a sheet which is both lighter and cheaper than the expensive ledger stock of which the body of the 90 sheet is made. Thus, no great increase of space is required for the storage of a ledger embodying the present invention, while at the same time this form of "pick-up" column slip enables a material economy of 95 labor, and an increased accuracy of work, and increased ease of handling the sheets.

Other features and advantages will hereinafter appear.

In the accompanying drawings, 105
Figure 1 is a perspective view of a sheet embodying my invention.

Figure 2 is a similar view of a transfer

balance column detached from another sheet, for the purpose of making the initial entry in the sheet of Figure 1.

Figure 3 is a view similar to Figure 1, 5 but showing the sheet at the end of the week with all the flaps thrown back onto the opposite face.

Figure 4 is a perspective view of the opposite face of the sheet after the entries of 10 Monday have been made and the transfer balance margin has been detached.

Figure 5 is a view of the detached flap embodying the transfer balance column of the face shown in Figure 1.

15 Figure 6 is a perspective on a small scale to illustrate one form of attachment of the flap to the sheet.

The ledger-sheet, herein shown, comprises a body portion 10, which has on each 20 of its faces a name column 11 and a series of day columns 12, there being one day column 12 for each day of the week, as seen in Figure 1. Each day column is further subdivided into a checks-deposit column 13 25 and a daily balance column 14, of which the former is adapted to receive the grouped item entries as they come in, and the latter is adapted to always show at its latest entry the current working balance.

30 At the beginning of a day's work on Monday, or at the close of books Saturday night, to make them ready for opening business on Monday, the Saturday transfer balance column 15 of the previous week's sheet was 35 placed alongside of or upon the face of the sheet 10 with the name rulings 16 in register, the flaps 17, 18 and 19 being thrown back clear of the face before the insertion of the sheet in a typewriting machine.

40 The first entry made was to copy the item \$1000 from the transfer balance column 15, and enter it upon the flap 20 which overlies the Tuesday day column 12. In doing this, certain computations are usually effected.— 45 not necessary to the present disclosure. The first active business entry on Monday was a deposit of \$1000. Preparatory to entering this active entry, the typist placed the sheet 10 in the typewriting machine, as folded in 50 Figure 1, and positioned the carriage to write in the "pick-up" column flap 20 and copied the amount \$1000 from the line above, adding it into the "computing" register commonly used in types of the Underwood 55 bookkeeping machines having two registers. One form of these machines embodying three registers is disclosed in the patent to Hoyt, No. 1,280,228, dated October 1, 1918.

60 Then the typist brought the carriage to write in the checks-deposits column 13 of the Monday day column 12, and entered therein the deposit or credit of \$1000, thus bringing the "computing" register to read \$2000, and causing the "footing" register to foot the 65 amount \$1000 at the same time. Then the

typist brought the carriage to write in the daily balance column 14 of the Monday day column 12 and subtracted out the \$2000 shown in the "computing" register, by writing it in said column, and then printed the 70 usual star to prove the accuracy of the work.

In the same general manner, the typist entered a charge of \$1900 by first positioning the carriage to write in the "pick-up" balance column 20 the last amount \$2000 then 75 shown in the daily balance column, and then brought the typewriter carriage to write in the checks-deposits column 13 of the Monday day column 12, and wrote therein the amount \$1900, subtracting it from both the registers, 80 thus bringing the "computing" register to read \$100. Then the typist brought the carriage to write in the daily balance column 14 of the Monday day column 12 and wrote therein the amount \$100 shown in the "com- 85 puting" register, causing it to subtract, thereby bringing said register to zero, and then printing the usual star to prove the accuracy of the work.

The "pick-up" balance column 19 occupies 90 part of an extension 21 of the sheet 10 which is folded down from the top line 22 thereof, at which line the extension may be pasted onto the body of the sheet, thus enabling a cheaper or lighter sheet to be used for the 95 "pick-up" balance columns than is used for the body of the sheet 10.

In order to enable a "pick-up" balance column flap 22^a, covering the Wednesday day column 12, to be used in making the entries 100 under Tuesday, the extension 21 is provided with a vertical perforated line 23, lying directly above the ruling 24 which separates the Tuesday column 12 from the Wednesday column 12, so that by severing 105 the extension or flap along the line 23, the flap 20 is free to be thrown back, bending over on its folded line 22, so that it lies against the opposite face of the sheet. To enable the other day columns to be used in 110 the same way, there are provided other perforated vertical lines 25, coinciding with the margin rulings of the day columns, so that each flap 18, 19, 20, etc., can be folded back individually.

115 At the right-hand end of the sheet, adjacent the Saturday day column 12, there is a transfer balance column 26, adapted to receive the transfer balances, to enable them to be conveniently copied onto the opposite 120 face of the sheet. Overlying this transfer balance column 26 is a "pick-up" balance column flap 27 adapted to serve as a "pick-up" balance column to compute the Saturday entries, and separated from the "pick-up" balance flap 22^a overlying the Saturday day column by a perforated line 28.

125 To open business on Monday of the following week, the opposite face of the sheet is used, and to enable it to be readily used, the 130

- flap 27 may be detached along its perforated line 28, thus permitting the transfer balance column 26 to be folded over, without detaching it, enabling the balances shown thereon 5 to be copied into the exactly aligned rulings on the opposite face of the sheet. If desired, the transfer column may be detached, as shown in Figure 5, instead of being folded over.
- 10 Since the name column 11 usually appears only on the left-hand margin of a sheet of this type, some of the day columns 12 on the opposite face of the sheet lie behind the name column 11 on the face of the sheet, shown 15 in Figure 1. To enable these day columns to be used readily, the flaps 17, 18 and 19 are formed as continuations of the same extension 21 as are the flaps 20, 22^a and 27. These flaps 17, 18 and 19 are provided with 20 perforated lines 29, 30 and 31 at their margins to enable them to be separated from the body of the extension 21 after being used individually.

The transfer balance column 15 of the 25 sheet 10 is behind the blank column 32, seen in Figure 1. The columns on the two faces of the sheet are so ruled that each day column coincides with a name or day column on the opposite face of the sheet, thus making 30 the handling of the "pick-up" balance flaps easy, and making it possible, if desired, to have more than one name column on each face.

It will be observed that the flaps forming 35 the extension 21 have one face used during one week and the opposite face used during the succeeding week, and that when the sheets are stored away the whole extension 21 may be detached along a perforated line, 40 which may be on or near the line 22, with the result that the sheets 10 occupy a minimum space for storage.

Variations may be resorted to within the 45 scope of the invention, and portions of the improvements may be used without others.

Having thus described my invention, I claim:

1. A ledger-sheet adapted for use in a printing and computing machine, divided 50 into designated day columns on each face of the sheet and having a writing strip attached to the top of the sheet overlying a day column and adapted to be folded down on either face of the sheet, and when so 55 folded down adapted to serve as a "pick-up" column for an adjacent day column.

2. A ledger-sheet adapted for use in a printing and computing machine, divided 60 into designated day columns on each face of the sheet and having a temporary sheet attached to the top of the ledger-sheet adapted to be folded down over a plurality 65 of day columns, and comprising perforations, so that it is adapted to be severed along the lines of each day column to en-

able it to be divided into writing strips, each adapted to serve as a "pick-up" column for an adjacent day column and to be detached from the rest of the temporary sheet along its side edge, when it is desired to use underlying day columns, and when so detached adapted to be folded over under the opposite face of the ledger-sheet. 70

3. A ledger-sheet for a printing and computing machine, comprising a plurality of 75 designated day columns on each face of the sheet and a writing strip adapted to overlie the day column adjacent the one in use, said strip being attached to the top of the sheet and adapted to be folded over to the 80 opposite face of the sheet, to be out of the way of the underlying day column and to enable the opposite face of the strip to be utilized as a "pick-up" column on the opposite face of the sheet. 85

4. A ledger-sheet for a printing and computing machine, comprising a plurality of 90 designated day columns on each face of the sheet and a writing strip adapted to overlie the day column adjacent the one in use, said 95 strip being attached to the top of the sheet and adapted to be folded over to the opposite face of the sheet, to expose the underlying day column and to enable the opposite face of the strip to be utilized as a "pick-up" column on the opposite face of the sheet, a designated transfer balance column on one face of the sheet, and a strip attached to the top of the sheet adapted to overlie 100 said transfer balance column, so that the strip may serve as a "pick-up" column for the adjacent day column, and may be turned over to the opposite face of the sheet to enable writing in the transfer balance column. 105

5. A ledger-sheet for a printing and computing machine, comprising a plurality of 110 designated day columns on each face of the sheet and a writing strip adapted to overlie the day column adjacent the one in use, said strip being attached to the top of the sheet 115 and adapted to be folded over to the opposite face of the sheet, to expose the underlying day column and to enable the opposite face of the strip to be utilized as a "pick-up" column on the opposite face of the sheet, a designated transfer balance column on each face of the sheet, and a strip attached to the top of the sheet adapted to overlie each transfer balance column, so that the strip may serve as a "pick-up" 120 column for the adjacent day column, and may be turned over to the opposite face of the sheet to enable writing in the transfer balance column, said transfer balance column being foldable over and detachable to 125 enable a transfer balance to be copied into the opposite face of the sheet.

6. A ledger-sheet for use with a computing and printing machine, comprising a plurality of 130 designated day columns upon each

face thereof and a designated name column of the width of a day column on each face and coinciding with a day column on the opposite face of the sheet, an extension of 5 said sheet attached to the top, writing strips forming said extension adapted to be folded over at the top, each strip being of the width of a day column, so that it overlies it, and, when overlying it, may serve as a "pick-up" 10 balance column for the adjacent day column, a designated transfer balance column at each margin of the sheet, and a strip adapted to overlie each transfer balance column to form 15 a "pick-up" column for the adjacent day column.

7. A ledger-sheet for use with a computing and printing machine, comprising a plurality of designated day columns upon each 20 face thereof and a designated name column on each face of the width of a day column and coinciding with a day column on the opposite face of the sheet, an extension of said sheet attached to the top, writing strips forming said extension adapted to be folded over at the top, each strip being of the width of a day column, so that it overlies it, and, when overlying it, may serve as a "pick-up" 25 balance column for the adjacent day column, a designated transfer balance column at each margin of the sheet, and a strip adapted to overlie each transfer balance column to form a "pick-up" column for the adjacent day column. 30

8. A ledger-sheet adapted for use in a 40 printing and computing machine, divided into superposed designated day columns on the opposite faces of the sheet and having a writing strip attached to the top of the sheet overlying and coinciding with a day 45 column, and adapted to be folded down on either face of the sheet, and when so folded down adapted to serve as a "pick-up" column for the adjacent day column.

9. A ledger-sheet adapted for use in a 50 printing and computing machine, divided into superposed designated day columns on the opposite faces of the sheet and having a temporary sheet attached to the top of the ledger-sheet adapted to be folded down over 55 a plurality of day columns, and comprising perforations, so that it is adapted to be severed along the lines of each day column to enable it to be divided into writing strips, each coinciding with a day column, each 60 adapted to serve as a "pick-up" column for

the adjacent day column and to be detached from the rest of the temporary sheet along its side edge, when it is desired to use underlying day columns, and when so detached adapted to be folded over under the opposite face of the ledger-sheet. 65

10. A ledger-sheet for use with a computing and printing machine, comprising a plurality of designated day columns upon each 70 face thereof and a designated name column of the width of a day column on each face thereof and coinciding with a day column on the opposite face of the sheet, an extension of said sheet attached to the top, writing strips forming said extension adapted to be 75 folded over at the top, and adapted to serve as a "pick-up" balance column for the adjacent day column, a designated transfer balance column at each margin of the sheet, and a strip adapted to overlie each transfer 80 balance column to form a "pick-up" column for the adjacent day column.

11. A ledger-sheet, for use in a printing and computing machine, divided on each face into designated day columns arranged 85 from side to side of the sheet, the day columns on the opposite faces of the sheet being in coincidence but in reverse order of designation, and having a writing strip attached to one end thereof so as to be foldable over each face and divided by suitable lines of demarcation into pick-up columns adapted 90 to coincide with the day columns on either face of the ledger-sheet when folded thereover, each column on the strip being detached therefrom and the underlying day 95 column exposed when typing is to be effected in the latter, the next pick-up column on the strip being used in connection with such typing and the computation associated 100 therewith.

12. A ledger-sheet, for use in a printing and computing machine, divided on each face into designated day columns arranged from side to side, the day columns on opposite faces being in coincidence but reversed 105 in order of designation, and having a plurality of pick-up columns attached to one end of the ledger-sheet so as to be foldable over either face thereof to cover up a day column thereon, the day column in which typing is to be effected being exposed by withdrawing a pick-up strip lying thereover, and the pick-up column over the next day 110 column being used to receive pick-up entries. 115
